UNITED STATES PATENT OFFICE.

HALLAH C. KINNISON, OF DALLAS, TEXAS.

VALVE.

SPECIFICATION forming part of Letters Patent No. 783,285, dated February 21, 1905.

Application filed October 15, 1904. Serial No. 228,618.

To all whom it may concern:

Be it known that I, HALLAH C. KINNISON, a citizen of the United States, residing at Dallas, in the county of Dallas and State of Texas, have invented new and useful Improvements in Valves, of which the following is a specification.

My invention relates to steam-heating systems in which vacuum-pumps are employed; and its primary object is to provide a novel and useful valve adapted to be interposed in the return-pipe between a radiator and a vacuum-pump, whereby a vacuum may be obtained and preserved in the radiator and whereby the discharge of condensation may be controlled and regulated.

A further object of the invention is to provide a valve of the above-stated character which is cheap to manufacture, simple of construction, durable, and efficient and which is composed of few parts so arranged and constructed as not to be liable to become broken or inoperative.

With the above and other objects in view the invention consists in the construction, combination, and arrangement of parts hereinafter fully described, claimed, and illustrated in the accompanying drawings, wherein is disclosed the preferred form of my invention, and wherein—

Figure 1 is a vertical central section of a valve constructed in accordance with my invention. Fig. 2 is a transverse section on the lines 2 2 of Fig. 1.

Referring to the drawings by reference-numerals, 1 designates an outer cylinder closed at its bottom except for an outlet or discharge opening 2, which communicates with a nipple 3, said nipple being provided with interiorly arranged screw-threads 4, whereby a vacuum-pump may be removably secured to the nipple. The cylinder is also provided, at a point adjacent its upper end, with screw-threads 5, adapted to be engaged by screw-threads of a cap 6, whereby said cap may be removably secured in applied position. This cap is provided with an upstanding projection 7 to permit of said cap being readily applied and removed by means of a tool. A cylinder 8 is arranged on the interior of said

cylinder 1 and is of a diameter smaller than that of the cylinder 1, whereby a space 9 is provided between the two cylinders. This cylinder is also of a length shorter than that of the cylinder 1 to provide a space between the upper and lower ends of the cylinder, and said cylinder 8 is suspended within the cylinder 1 by means of an integral connection 10. The cylinder 8 is closed at its bottom except for an opening 11, which flares upwardly to provide a conically-shaped valve-seat 12, said opening and valve-seat registering with the opening 2 in the cylinder 1. The upper end of the cylinder 8 is provided with screw-threads adapted to be engaged by the screw-threaded edge of a cap 13, whereby said cap may be removably secured in applied position, this cap being also provided with a projection 14, similar in construction to the projection 7. Projecting laterally from the cylinder 1 and communicating with the interior of the cylinder 8 is a sleeve 15, having its end provided with screw-threads 16, whereby said sleeve may be connected to a radiator by the usual coupling. The cap 12 is provided with air-escape openings 17, whereby communication is set up between the two cylinders.

A float 18 is movable in the cylinder 8 and has its upper and lower ends provided with guide-rods 19 and 20, respectively. The guide-rod 19 is movable in a recess 21, arranged in the cap 13 and the guide-rod 20 is movable in the opening 11, whereby said float is adapted for vertical movement. The guide-rod 20 is provided with a conical valve 22, adapted to normally occupy the valve-seat 12.

The valve, as above described, is adapted to be interposed in the return-pipe of a steam-heating system between a vacuum-pump and a radiator. The vacuum-pump is set in operation and the air in the radiator is caused to pass through the sleeve 15 into the cylinder 8, then through the openings 17 and 2 into the vacuum-pump, from whence it is discharged. After the air is exhausted from the radiator the steam is permitted to enter the same, and as the condensation accumulates in the radiator it passes into the cylinder 8 through the medium of the sleeve 15. When a sufficient amount of condensation has accumulated in

the cylinder 8, the float 18 is caused to rise, thereby unseating the valve 22 and permitting the condensation to flow through the openings 11 and 2 into the vacuum-pump. It is apparent that the air may at all times be exhausted from the radiator without disturbing the valve 22, whereby at all times a vacuum may be maintained and the discharge of condensation may be effectually regulated and controlled. It is also apparent that as the cylinders 1 and 8 are curved downwardly toward their centers all liability of condensation accumulating in the cylinder 1 is obviated and that when the valve 22 is unseated all of the condensation in the cylinder 8 will be discharged through the opening 11.

Having thus fully described the invention, what is claimed as new is—

1. In a valve for a heating system, an outer cylinder closed at its upper end and provided with a discharge-opening at its lower end, said cylinder being provided with means whereby it may be interposed between a radiator and a vacuum-pump, an inner cylinder arranged within and spaced from the outer cylinder, said inner cylinder being provided at its upper end with an air-discharge opening and at its lower end with a condensation-discharge opening, and a valve mounted within the in-

ner cylinder and regulated by condensation to control the condensation-discharge opening.

2. In a valve for a heating system, an outer cylinder provided at its lower end with a discharge-opening, and provided with means whereby said cylinder may be interposed between a radiator and a vacuum-pump, a cap removably secured to the upper end of said cylinder, an inner cylinder arranged within and spaced from the outer cylinder and provided with a condensation-discharge opening in its lower end, said discharge-opening tapering upwardly and outwardly to provide a conical valve-seat, a cap removably secured to the upper end of said inner cylinder and provided with air-discharge openings, said last-named cap being provided with a recess, a float arranged within the inner cylinder and provided at its upper and lower ends with guide-rods, and a valve secured to said lower guide-rod and adapted to normally occupy said valve-seat.

In testimony whereof I affix my signature in presence of two witnesses.

HALLAH C. KINNISON.
